UNITED STATES PATENT OFFICE

EMIL S. SCHENKEL, OF NEW YORK, N. Y.

SIGN ILLUMINATION

Application filed August 19, 1932. Serial No. 629,432.

This invention relates to signs; more particularly, to illuminated signs.

It is an object of my invention to provide a sign for advertising and exhibit purposes which is easy to manufacture, and constructed of relatively inexpensive material, but which in its essential features exhibits all the attractive elements of highly expensive illuminated signs. Thus, it is contemplated by my invention to provide a sign construction in which the letters or other graphic representations give the illusion of considerable depth, and where used for exhibit or advertising purposes, the letters thereof, even though made upon the surface mounting the same by flat surfacing treatment, give the appearance of considerable depth, and therefore are more conspicuous, prominent and attractive, when viewed by transmitted or reflected light.

Still further objects of my invention reside in the provision of a sign construction in which the graphic representations, comprising letters, words or similar characters, may be supported upon a supporting base of flat material, such as glass, paper, parchment, celluloid or the like, whereby these may be applied by a simple and inexpensive surfacing operation, such as by printing, coating, painting or the like, and upon illumination, either by transmitted or reflected light, give the illusion of depth and shaded effect simulating blocked letters or gas filled tubes.

To attain these objects and such further objects as may appear herein or be herein-after pointed out, I make reference to the accompanying drawing, forming a part hereof, in which—

Figure 1 is a face view of my device;
Figure 2 is a perspective view thereof;
Figure 3 is a vertical section of my device;
Figure 4 is an enlarged fragmentary horizontal section;

Figure 5 is an enlarged perspective view of a detail;

Figure 6 is an enlarged perspective view of a detail of another embodiment of my invention;

Figure 7 is a sectional view through another embodiment of my invention.

Making reference to the drawing, the device as contemplated by me, in its preferred form, comprises a housing 10, preferably made of sheet metal, with brilliant internal surfaces 11, such as obtained by tinned metal, within which there is arranged to be contained a source of illumination 12, such as an incandescent bulb mounted within a socket 13, having a source of electrical current 14. This may also include a flickering device 60 of well-known construction.

The housing 10 is open at its front face 15, and is formed with a framing element 16 of pleasing appearance and shape. Rearwardly of the frame there is provided a pair 65 of grooved frames 17 and 18, the housing being slotted at 19 and 20 to provide access to these grooved frames, for purposes which will appear more clearly as this description 70 proceeds.

Within the frames 17 and 18, a sign plate may be arranged, visibility being enhanced by transmitted light, whenever the lamp 12 is luminous.

With such construction, in its preferred form, I provide within the grooved frame 11 a sign element 21, and forwardly spaced therefrom a second sign element 22. The essential element of my sign construction lies in the general relationship of the sign elements 21 and 22, and therefore more particular reference will now be made thereto.

The sign element 21 is preferably composed of a sheeted material. This may be glass, celluloid, oiled or parchmentized paper or similar material. It is preferred, however, that the sheet 21 be made of parchmentized paper or board which has been rendered translucent, to give an even light distributing effect by impregnating the same 85 with a thin water-white lubricating oil, such as mineral oil.

In the production of a sign element of this character, I first print upon the sign element 21, which is preferably parchmentized paper or board of the character above described, outlines of the graphic representations or letters 24. This may be accomplished by a printing operation using a dye. Where a colored effect is desired, and the colors pref- 100

erably chosen such as those usually employed in gas filled tubes, the coloring material which is utilized is a transparent dye which colors the paper without modifying the 5 translucency of the paper or backing material. Over the section outlined by the printed portions 24, or where a white effect is desired, this may be untreated, there is then applied a stencil outline 25, blocking out the 10 characters defined by the portion 24. The blocked out portions 25 are applied by a printing operation, using a heavy, opaque printing ink and this, for purposes of contrast is preferably black. The printing operation 15 may be effected by a silk screen method. Subsequently, this sheet is then rendered translucent by dipping the same into an oily mixture, such as a light weight mineral oil, or paraffin oil. The excess is then squeezed 20 out of the paper and the sheet is ready for use.

The sign element 22 is arranged to be of substantially exactly the same size as the element 21. This element is preferably made 25 of a transparent sheeting, such as glass, transparent celluloid or regenerated cellulose, which may comprise the product known on the market as cellophane. Upon this sheet 22 there is outlined the graphic characters 26, by a printing or surfacing operation, such as spraying stencilling or the screen process previously referred to. The characters 26 are preferably made of a coating material of opaque character, such as opaque printing 30 ink and the characters 26 are arranged upon the sheet so as to be substantially in registry with the outline of the characters 24, on the sheet 21.

The construction as described provides two 40 spaced sheeted materials with a pair of characters in spaced relationship, preferably in registry with each other, the rearward one being capable of being illuminated by transmitted light from the source 12, and the 45 forward one being capable of illumination by reflected light. The effect produced when the sign is viewed from a slight angle, to one side, or below or above the characters is that of substantial depth and shaded effect of the 50 letters, simulating heavily blocked out characters or letters. This I attribute, to some extent, to the fact that the front sign element 22, particularly where this is made of glass, provides a rearward reflective surface, par- 55 ticularly where the characters 26 are made of opaque material, to give the illusion of a continuous stream of light between the spaces defined by the elements 21 and 22. This effect, coupled with the transparency of the 60 element 22 and the opaque black background formed by the portion 25 of the rear element 21, gives to the surface coatings of each of the elements the third dimensional effect.

To further accentuate the depth or third 65 dimensional effect of the characters defining

the graphic representations or letters, especially where the sign element is to be viewed directly from the front, absolute registry of the portions 24 and 26 need not be made, and a slight offset arrangement of the elements 21 70 and 22 may be made.

It is also contemplated by me to arrange the portions defining the characters upon the sign elements 21 and 22 in alignment, to obtain the third dimensional effect, by outlining 75 the characters 26 on the front element 22 slightly smaller than the elements 24 in the rear sheeted member 21.

In the embodiment disclosed in Figure 6, the same construction may be utilized as previously described. However, in this embodiment I may form the characters 26a of a coating composition which is somewhat translucent. In this embodiment I prefer to form 80 at the outlines of the characters 26 a narrow stripping 27, and this is preferably formed by an opaque printing ink or paint. When this embodiment is viewed with transmitted light obtained from the lamp 12, the third dimensional effect will be accentuated, and 85 when the sign is viewed by reflected light only, from the forward portion of the sign, the outline of the characters 26 will be more definite.

It will further be observed that though in 90 the particular embodiment as illustrated in Figure 6 the characters 26a may be formed of some translucent paint or printing ink, I may also utilize an opaque coating material, as in the prior embodiment.

It will further be observed that though I have described the sign element as made from two separately spaced sheeted materials 21 and 22, a single sheeting may be used and in this form, a heavier plate of glass, having the requisite spacing between the front face and the rear face, may be utilized. In this embodiment, the rear face of the sheeting is covered with the opaque material corresponding to the coating 25, outlining the characters 24 by a transparent space or dyed transparent coating and the front face is coated at the spaces corresponding to the sections 26, with an opaque printing ink or paint.

In Figure 7 I have disclosed an additional embodiment, and in this construction 28 comprises a plate, preferably of glass, the rear face 29 whereof is coated with an opaque printing ink or paint 30, outlining a character 31. The front face 32 has applied at 33 characters defined by the spaces formed at 31, to be in direct registry with these portions, or slightly offset, in a manner previously described.

This embodiment will serve to give to the illuminated portions 31 the third dimensional effect, to some degree, as previously described.

I may also associate in connection with the embodiment illustrated and described in connection with Figure 7, an independent sign 130

element 34, made of oiled parchmentized paper, in accordance with the prior embodiments described by me, in which the opaque sections outlining the characters are shown at 35, leaving the translucent portions 36 outlining the characters or graphic representations. When I associate the sheeting 34 with the plate 28, to the rear thereof, in spaced relationship therewith, I may omit the coating 30, and preferably apply to the space 31, outlining the characters on the rear surface 29 of the plate 28, an additional coating outlining the characters corresponding to the spaces provided at the portions 33 on the front face 32 of the plate and that formed at 36 on the sheet 34. This coating is preferably of a translucent printing ink or paint. This construction, as described, further accentuates the third dimensional effect of the characters coated upon the sign element.

20 It will further be observed that though it is contemplated by me, in my preferred form, to assemble two sheeted elements, the rear one of which includes an opaque stencil outlining transparent or translucent characters, and a front element having characters in registry therewith and formed by coating, leaving other portions transparent or translucent, to give an appearance of depth or substantial thickness and the illusion of characters made by blocking out heavy wood, glass or tubes, I may assemble a plurality of such members, as generally defined by the element 22 forwardly of the sign element 21, and where 25 such construction is provided, it is preferred that the coating material used to outline the characters be of translucent paint or dye and of a color compatible with that which outlines the characters 24, and as nearly identical 30 therewith in shade as to impart to this intermediate section a continuity of characters from the rear element 21 to the forward element 22.

It will thus be observed that I have provided a new and novel sign, of simple construction, which provides all the essentials and desirable characteristics for imparting distinctiveness and attractiveness, and which gives the impression of a much more expensive device.

Having thus described my invention and illustrated its use, what I claim as new and desire to secure by Letters Patent, is—

1. In an illuminated sign, in combination 55 with a light source, a pair of sign elements carrying graphic representations, said sign elements comprising spaced translucent surfaces, one surface defining the characters by an opaque printed stencil being positioned adjacent the light source, the other carrying printed characters in substantial registry therewith, leaving the remainder of the surfaces substantially unmodified for simultaneously viewing the characters of both surfaces.

2. In an illuminated sign, in combination with a light source, a plurality of sign elements comprising surface coatings defining letters or characters in spaced relation and in substantial registry, the coating of one surface being substantially opaque and mounted upon a transparent sheeting, the other coating being opaque stencil and disposed between the light source and the first surface. 70

3. In an illuminated sign, in combination with a light source, a plurality of sign elements comprising surface coatings defining letters or characters in spaced relation and in substantial registry, the coating of one surface being substantially opaque and mounted upon a transparent sheeting, the other coating being an opaque stencil and disposed between the light source and the first surface, the stencil coat being formed upon a substantially translucent sheeting. 75

4. In an illuminated sign, in combination with a light source, a plurality of sign elements comprising surface coatings defining letters or characters in spaced relation and in substantial registry, the coating of one surface being substantially opaque and mounted upon a transparent sheeting, the other coating being an opaque stencil and disposed between the light source and the first surface, the stencil coat being formed upon a substantially translucent sheeting, the translucent sheeting and coating of the first mentioned surface being shades of the same color. 80

5. In an illuminated sign, a sign element 95 for letters or characters comprising a substantially transparent sheet, the opposite spaced surfaces whereof include a surface coated portion outlining letters or characters by an opaque coating material to leave the letters or characters visible by transmitted translucent light, the opposite surface including a coating substantially in registry with that outlined by the opposite coating, leaving the remainder of the surface transparent. 100

6. In an illuminated sign, sign elements therefor, comprising a light transmitting portion defining letters or characters upon an opaque background, and a forwardly positioned transparent surface supporting a coating defining identical letters or characters with the first letters or characters mentioned, and overlying the light transmitting portion and spaced therefrom, whereby the second coating and light transmitting portions may be simultaneously viewed. 115

7. In an illuminated sign, sign elements therefor, comprising a light transmitting portion defining letters or characters upon an opaque background, and a forwardly positioned transparent surface supporting a coating defining identical letters or characters with the first letters or characters mentioned, and overlying the light transmitting portion and spaced therefrom, whereby the second 120 125 130

coating and light transmitting portions may be simultaneously viewed, the second coating being of a substantially similar color.

8. In an illuminated sign, sign elements therefor, comprising a light transmitting portion defining letters or characters upon an opaque background, and a forwardly positioned transparent surface supporting a coating defining identical letters or characters with the first letters or characters mentioned, and overlying the light transmitting portion and spaced therefrom, whereby the second coating and light transmitting portions may be simultaneously viewed, the second coating being of a substantially similar color, and formed of opaque coating material.

9. In an illuminated sign, sign elements therefor, comprising a light transmitting portion defining letters or characters upon an opaque background, and a forwardly positioned transparent surface supporting a coating defining identical letters or characters with the first letters or characters mentioned, and overlying the light transmitting portion and spaced therefrom, whereby the second coating and light transmitting portions may be simultaneously viewed, the second coating being of a substantially similar color, and opaque outlines for said second coating.

30 In witness whereof, I have hereunto signed my name this 17th day of August, 1982.

EMIL S. SCHENKEL.
